224,396

SEAL RETAINING MEMBER FOR A ROLLER SHUTTER

Donald Henry William Dover, "Igls," The Ridge, Little Baddow, near Chelmsford, England

Filed Sept. 21, 1970, Ser. No. 25,097

Term of patent 14 years

Int. Cl. D25—01

U.S. Cl. D13—6

FIG. 1.

FIG. 2.

FIG. 1 depicts a perspective view of the seal retaining member, and

FIG. 2 is a section of the seal retaining member shown in FIG. 1.

I claim:

The ornamental design for a seal retaining member for a roller shutter, substantially as shown and described.

References Cited

UNITED STATES PATENTS

3,493,032 2/1970 Brown, Jr. et al. ----- 160—201
1,528,147 3/1925 Durkee.

OTHER REFERENCES

Loxit Metal Mouldings catalog No. 3-48.

A. HUGO WORD, Primary Examiner